UNITED STATES PATENT OFFICE.

CHARLES EDWARD GATE, OF WINNIPEG, MANITOBA, CANADA.

CLEAN-OUT PLUG.

1,304,174.

Specification of Letters Patent.

Patented May 20, 1919.

Application filed March 23, 1918. Serial No. 224,258.

To all whom it may concern:

Be it known that I, CHARLES EDWARD GATE, of the city of Winnipeg, in the Province of Manitoba, Canada, have invented certain new and useful Improvements in Clean-Out Plugs, of which the following is the specification.

The invention relates to improvements in cleanout plugs especially as utilized with sewer pipes and the principal object of the invention is to provide a plug which will effectively close the pipe in which it is inserted and which can be easily removed when one desires to clean the sewer pipe.

15 A further object of the invention is to construct the plug so that the sewer gases and moisture in the pipe can in no way harm the working parts of the plug.

With the above more important and other minor objects in view the invention consists essentially in the arrangement and construction of parts hereinafter more particularly described and later pointed out in the appended claims, reference being had to the accompanying drawings in which:

Figure 1 represents a fragmentary portion of the sewer pipe showing my invention installed.

Fig. 2 represents an enlarged detailed vertical sectional view through the cleanout plug.

Fig. 3 represents a horizontal sectional view through the cleanout plug and looking upwardly, the section being taken in the plane denoted by the line X-X' Fig. 1.

Fig. 4 represents a sectional view through the plug at X-X' and looking downwardly.

Fig. 5 represents a fragmentary portion of the upper end of the ring or collar.

40 Fig. 6 represents a vertical sectional view through a modified form of plug.

Fig. 7 represents the modified form of plug as utilized on a trap.

Fig. 8 represents an inverted plan view of the modified form of plug with the cap or cover removed.

In the drawings like characters of reference indicate corresponding parts in the several figures.

50 1 represents a main sewer pipe which is provided with a branching sewer cleanout pipe 2, a trap 3 and trap cleanout plug 4, this latter plug being of the ordinary screw type and being provided to allow of entrance to the trap. The branch or sewer cleanout pipe 2 is formed with the usual flaring head

5 and shoulder or seat 5' and is closed with my plug as now described in detail.

6 represents an upwardly tapering ring or collar having the lower end formed with an 60 inturned flange forming a valve seat 7 and the upper end provided with four out-turned lips or lugs 8 for a purpose later disclosed.

This collar is inserted within the upper end of the cleanout pipe with the lower end 65 bearing on the shoulder and is held in fixed positions within the pipe in any suitable manner such as by locking as indicated at 9.

10 represents a cover or cap for the upper end of the collar which cap is provided with 70 a downturned rim 11 fitted with an inwardly turned flange 12 which is recessed or slotted in four places as indicated at 13 to allow of the lugs 8 to pass through and take a position above the flange 12 when the cover is 75 applied.

From this arrangement it will be obvious that if one has applied the cover as above disclosed he can lock it against release by turning it until the lug passes away from 80 the slots.

Centrally and on the underside the cover is provided with a bridge piece or bracket 14 presenting a horizontal bearing 15 through which I pass a vertically disposed valve stem 85 16 having the opposite ends threaded and supplied with nuts 17 and 18.

The lower end of the stem carries the valve 19 which is constructed from a lower metallic disk 20 and an upper metallic disk 90 21 between which I have placed a rubber disk 22. The under disk is somewhat smaller than the other disks so that the top metallic disk and the rubber disk overhang the bottom disk whereby when the valve is seated 95 the under face of the rubber disk bears on the valve seat and the under disk is received within the flange forming the valve seat.

In assembling the valve I wish the top disk to be screwed into position on to the 100 lower end of the valve stem and the rubber disk and under disk to be slipped into position on the stem so that when the nut 18 is tightened up the under disk will jam the rubber disk against the top disk.

105 23 represents a spiral spring mounted on the valve stem between the bracket and the upper side of the valve. This spring is gaged so that when it is inert or not under compression the released cover is held elevated, 110 that is to say with the flange 12 somewhat above the out-turned lugs 8.

24 represents a handle for the cover comprising a rod having the ends thereof bent at right angles to the body and passed through suitable holes 25 provided in the 5 cover and the extremities of the rod turned outwardly at 26 to form stops. Normally the weight of the handle holds it in the position shown, that is against the cover.

When it is to be used it is pulled out until 10 the stops engage the underside of the cover.

From the above disclosure it will be apparent that the ring or collar is a permanent fixture in the pipe and that the cover with the valve are removable.

15 When one wishes to close the pipe with my plug he simply inserts the valve until it seats on the valve seat and then forces the cap down against the action of the spring until the lugs 8 have been passed through 20 the slots 13, after which the cover is turned and becomes locked.

Obviously when the operation is complete the spring is under compression and serves to hold the valve effectively closed. Once 25 installed it will be seen that neither the sewer gases nor the moisture in the sewer pipe can effect the working parts of the plug as they are closed off entirely by the valve.

The removing of the plug is a simple operation as one has simply to turn the cap until the lugs reach the slots at which time the spring operates to release the cap. Then by pulling the handle outwardly one can lift the whole device clear of the pipe.

35 In Figs. 6, 7 and 8 of the drawings I have shown this plug as modified slightly so that it can be utilized as a plug for a trap such as a wash basin trap.

In the modified form the collar, cap and 40 valve are the same construction as hereinbefore disclosed with the exception that one end of the valve stem is projected slidably through the cap. Then, instead of supplying a spiral spring, I provide a pair of 45 crossed more or less V-shaped springs 27 and 28 which are mounted on the valve stem above the cap and have their outstanding ends terminating in foot pieces 29 bearing on the then underside of the valve, the 50 springs being designed to be normally under compression and holding the valve closed.

The collar in this instance is soldered or otherwise secured to the trap 30 communicating with the bowl 31.

What I claim as my invention is:—

55

1. The combination with a pipe, of a cleanout plug comprising a collar inserted within the end of the pipe and provided at the inner end with a valve seat, a cap detachably secured to the outer end of the collar and a spring pressed valve carried by the cap and engageable with the valve seat in a manner such that the spring is under compression when the cap is applied.

60

2. The combination with a pipe, of a 65 collar permanently inserted within the end of the pipe and provided at the inner end with an inturned flange forming a valve seat, a cap releasably secured to the outer end of the collar and a spring pressed disk 70 like valve carried by the cap and engaging the valve seat, said spring being under compression and holding the valve to the seat when the cap is applied.

75

3. The combination with a pipe, of a collar permanently secured within the end of the pipe and provided with an inturned flange forming a valve seat, a cap detachably secured to the outer end of the collar, a slidably mounted valve stem carried by 80 the cap, a valve carried by the inner end of the valve stem and a coiled spring located on the valve stem and interposed between the cap and the valve and designed, when the cap is finally applied on the collar, to be 85 under compression and holding the valve tightly seated against the valve seat.

80

4. The combination with a pipe, of a collar permanently secured with the end of the pipe and provided at the inner end with an 90 inturned flange forming a valve seat, a cap detachably secured to the outer end of the collar, a bracket located centrally on the inner side of the cap, a valve stem slidably mounted in the bracket and provided at the 95 opposite ends with outer and inner adjusting nuts, a disk like valve secured to the inner end of the stem by the innermost adjusting nut and a spring interposed between the valve and the cap and designed to hold the 100 valve pressed tightly against the valve seat in the finally applied position of the cap.

100

Signed at Winnipeg, this 27th day of December, 1917.

CHARLES EDWARD GATE.

In the presence of—

G. S. ROXBURGH,
K. B. WAKEFIELD.
